OF MAINE.

APPARATUS FOR THE CONVERSION OF PEAT INTO COAL.

1,175,944.

Specification of Letters Patent.

Patented Mar. 21, 1916.

Application filed January 21, 1914. Serial No. 813,421.

To all whom it may concern:

Be it known that we, OLPHA A. FORD, of Everett, county of Middlesex, and Commonwealth of Massachusetts, and JEREMIAH C. LONG, of Everett, in the county of Middlesex and said Commonwealth, both citizens of the United States, have invented certain new and useful Improvements in Apparatus for the Conversion of Peat into Coal, of which 10 the following is a full, clear, and exact description.

This invention has for its purpose the devising of improvements in the apparatus for preparing peat for use as fuel, and for the 15 utilization and salvage of the by-products therefrom.

In preparing peat for fuel, there are two mainsteps in the process, the first comprising the extraction of the moisture contained 20 therein, and the second the formation of the same into briquets. In order to dry the peat with sufficient rapidity to render the utilization of apparatus economical, it is necessary to employ a current of air or the like for 25 passing over and through the peat, which shall be heated to quite a high temperature. In the employment of atmospheric air for this purpose there is considerable danger of either actual or partial combustion, owing 30 to the large proportion of oxygen in the air. To obviate such danger, and to obtain certain other beneficial results hereinafter set forth, we have devised means for supplying to the moist peat a hot gas incapable of feeding 35 combustion. The process therefor, and the apparatus devised by us for carrying the same into effect, as well as for accomplishing the hereinafter described improvements in process and apparatus, are as follows, 40 reference being had to the accompanying drawings, in which—

Figure 1 is a side sectional elevation of apparatus employed in carrying out our invention. Fig. 2 is a cross section on the line 45 X—X in Fig. 1.

The peat to be dried is fed to the inclined rotary drum 1 from the hopper 2, the delivery from the latter being aided by the stirrer 3 and feed belt 4. Said drum is rotated by any suitable means, as the motor 5 geared to the annular rack 6, and is supported by antifriction rolls 7, as illustrated in Fig. 2. This drum is surrounded by a sleeve 9 rigid therewith and of a sufficiently

larger diameter to leave an annular space 55 between.

To aid in the descent of the peat down the length of the drum as the latter slowly revolves, and more thoroughly to bring it into contact with the hot gases which are fed up 60 through the drum, the latter is provided with a helical rib 10 extending from end to end thereof within it.

For providing hot gases which will be practically without free oxygen, a furnace 11 65 is connected through a goose-neck 12 with the lower end of said drum so that the products of combustion therefrom pass up through the drum and the pipe 13 to a stack 14. The gases from the furnace are kept 70 from being objectionably hot, and at the same time such excess of heat is converted into useful work, by boiler tubes 14 located in the boiler 15, the gases passing through said tubes in the usual manner, and the 75 steam generated thereby being conveyed to the pumps employed in other parts of the process.

The proper temperature of gases delivered to the drum having been maintained, the 80 dried lumps of peat will emerge from the lower end of said drum to the upper part of the goose-neck 12 and descend through a chute 16 to the grinder 17. To keep the temperature within the drum of the proper 85 temperature, we locate a thermostat 20 within it, and provide a trap door 21 controlled thereby opening from the goose neck into the annular space 28. The upper end 90 of said space, or cut out conduit, connects with the pipe 13, so that the gases admitted to said conduit escape therefrom to the stack, and consequently relieve the peat within the drum of a sufficient amount of heat to keep it at the right temperature. Simultaneously 95 with such movement of the trap door, a damper 22 is arranged to close more or less the exit from the goose-neck to the drum in order to compel the diversion of the gases referred to.

The form of thermostat selected for illustration, and one which best seems fitted to its location, consists of a tube of steel or other less-expansive metal 20, rigidly held at 24, and carrying within it a rod 23 composed of some metal having a much greater coefficient of expansion; the upper ends of said tube and rod being fastened together,

and the lower end of said rod engages the short lever-arm 25 of the damper, whereby the longitudinal expansion of said rod causes the damper to close, and the latter, through 5 a bar 26, opens the trap-door 21. Further to insure the desired uniformity of temperature, the furnace or heater 11 is given a directly connected stack 27 having a damper 29 controlled through a chain 30 to open 10 as the damper 22 approaches its point of closure. Hence, if the diversion of the heat through the sleeve 9 is insufficient at any moment to reduce the temperature within the drum, the damper 29 is opened and the 15 products of combustion permitted to escape direct to the atmosphere.

The grinder 17 into which the dried lumps and fragments of peat descend is represented as of the well known mill-stone type, 20 as well fitted for the purpose; the pulverized peat passing therefrom to a receptacle 31, and thence to the briquet machine. The latter comprises a plurality of plungers 32 each forcing the pulverized material into its 25 individual die or tube 33, the stroke of the plungers being quite short, and said tubes being very long in comparison, so that the friction of the briquets therein will provide ample back-pressure for the compression of 30 the peat engaged by the plungers.

About the tubes or dies 33 are preferably three containers 37; the container 37^a being first filled with steam or hot water to raise the pulverized peat to the proper temperature 35 for perfect cohesion under pressure, when the press first begins. In a short time, however, the friction and compression so heat up the parts that it is necessary to fill said container 37^a with moderately cool 40 water for maintaining a temperature neither too hot nor too cold for the purpose. The second container 37^b is filled with colder water, and the third container 37^c is filled with very cold water, preferably a strong solution of brine, in order that when the briquets are finally delivered to the bin 40 they shall be cold and hard.

While the peat is being heated and dried in the drum, various volatile oils and other 50 hydrocarbons pass off therefrom to the stack and are lost. Further, the products of combustion from the furnace also contain certain elements which similarly pass off and are lost. To save such of these by-products 55 as are commercially useful, we provide the following apparatus: From the pipe section 13 descends a branch pipe 41 provided with a damper 42, and containing a suction fan 43 suitably rotated; the lower end of said 60 branch opening into a condenser 44 the circulation water for which is provided by a pump 45, and escapes through the discharge 46. The condensate descends to the hot well 47, from which it is taken by the wet vacuum pump 49 and discharged into the container

50. From the container the condensate can be removed when desired and separated by distillation into the several by-products composing it. Whatever gases there are which refuse to condense, are withdrawn 70 from the condenser by pump 51 and forced to the atmosphere through the stack, or they may be delivered to the gasometer 52 for preservation, if found sufficiently valuable. When thus using the condenser, the damper 53 is wholly or partially closed; and when 75 not in use, said damper is open, and the damper 42 is closed.

It should be noted that when the hopper 2 is filled with wet peat, practically no admittance of the atmosphere is possible through it, but the same forms a water-seal. Consequently, the damper 53 being tightly closed and the suction fan 43 being in rapid operation, there will be a partial vacuum in the 80 drum 1, since said fan can take care of more gas than that coming from the furnace and from the peat being treated in the drum. This partial vacuum aids considerably in the escape of the moisture and volatile gases 85 from the peat, and permits of the successful drying thereof at a lower temperature than would otherwise be necessary, thereby reducing the danger of injury to the fuel-quality of the peat. 95

What we claim is:

1. The herein described apparatus for converting peat into coal, which comprises an elongated drum having means for propelling peat from one end to the other thereof, means for delivering hot gas into the end of the drum toward which the peat is propelled, means for delivering peat into the other end of said drum, means for maintaining a reduced atmospheric pressure 100 within the drum, and means for receiving the dried peat from said drum without admitting air thereto, said peat-delivery means being constructed for continuous feeding 105 without admitting air therewith. 110

2. The herein described apparatus for converting peat into coal, which comprises an elongated drum having means for propelling peat from one end to the other thereof, means for delivering hot gas into the end of the drum toward which the peat is propelled, means for delivering peat into the other end of said drum, means for producing a suction acting at the peat-receiving 115 end of the drum, and means for receiving and grinding the dried peat and delivering it to a suitable receiver, without the admission thereto of atmospheric air. 120

3. The herein described apparatus for converting peat into coal, which comprises an elongated drum having means for propelling peat from one end to the other, means for delivering hot gas to the end of the drum toward which the peat is propelled, a sleeve surrounding said drum and forming 125

- an annular space about the same, and controlled means for diverting to said annular space a portion of the hot gas being delivered to said drum.
- 5 4. The herein described apparatus for converting peat into coal, which comprises an elongated drum having means for propelling peat from one end to the other, means for delivering hot gas to the end of 10 the drum toward which the peat is propelled, a sleeve surrounding said drum and forming an annular space about the same, adjustable means for diverting to said annular space a portion of the hot gas being delivered to said drum, and a thermostat 15 controlling said adjustable means.
5. The herein described apparatus for converting peat into coal, which comprises an elongated drum having means for propelling peat from one end to the other, a spaced sleeve surrounding said drum, means 20 for rotating said drum and sleeve, stationary conduits for delivering hot gas to said drum and sleeve, a damper between said 25 conduits, a damper controlling the conduit to said drum, and means for simultaneously closing one damper and opening the other.
6. The herein described apparatus for converting peat into coal, which comprises
- an elongated drum having means for propelling peat from one end to the other, a spaced sleeve surrounding said drum, means for rotating said drum and sleeve, stationary conduits for delivering hot gas to said drum and sleeve, a damper controlling each 30 conduit, and a thermostat for simultaneously opening and closing said dampers.
7. The herein described apparatus for converting peat into coal, which comprises a rotatable drum having means for propelling peat from one end to the other thereof, means for delivering hot gas into the end of said drum toward which the peat is propelled, and for receiving it from the other end, and means for feeding peat 40 into the last-referred to end, said feeding means comprising a stationary hopper, a feeding wheel in the latter, and an endless conveyer disposed below said wheel and having one end within the drum. 50

In testimony that we claim the foregoing invention, we have hereunto set our hands this 19th day of January, 1914.

OLPHA A. FORD.
